UNITED STATES PATENT OFFICE.

GEORGE WILLIAM WEAVER, OF ST. JOSEPH, MISSOURI.

WORKINGMAN'S GARMENT.

1,409,805.

Specification of Letters Patent. Patented Mar. 14, 1922.

Application filed August 10, 1920. Serial No. 402,617.

To all whom it may concern:

Be it known that I, GEORGE WILLIAM WEAVER, a citizen of the United States, residing at St. Joseph, in the county of Buchanan and State of Missouri, have invented certain new and useful Improvements in Workingmen's Garments, of which the following is a specification.

This invention relates to certain new and useful improvements in workingmen's garments and it has for its objects among others to provide a simple, cheap yet efficient one-piece garment, the suspender straps of which can be easily unsnapped from their connection above the pockets on the chest, and the entire seat portion can then be dropped down without the wearer taking off the entire upper part of the garment, the drop seat portion being cut in such a way that it answers the same purpose as the one-piece garment with the closed back, yet making it entirely convenient when necessary to drop the seat portion. In the present improvement the seat portion does not drop from the waistband as heretofore, yet it makes a neat fitting and appearing garment readily put on or taken off and one that is not liable to become damaged under heavy strains.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which—

Like numerals of reference indicate like parts throughout the different views.

Referring to the drawings, 1, 1 designate the legs of the trousers portion, and 2 the belt or waistband portion to which is attached the coat portion 3 by suitable lines of stitching. The coat portion is provided with pockets 4 which, in this instance, are shown as provided with flaps 5 secured in position by buttons and button-holes 6, while 7 are buttons at the top of the flap portions, as seen in Figure 1, and with which are designed to be engaged the fastening means on the ends of the suspender straps. These 60 suspender straps 8 are designed to extend over the shoulders, being crossed at the back of the garment and provided at their free ends with suitable means, as 9, for ready detachable engagement with the buttons 7 at 65 the front.

The suspender straps 8 are continuous of the drop seat portion 10 which is integral with the leg portions 1 at the rear, as seen in Figures 2 and 3, being separated therefrom at the sides from a point a considerable distance below the waistband, as at 11, see Figure 2, and provided along the sides 12 with buttons 13 adapted to be engaged in the button-holes 14 in the side portions 75 15, as seen in Figures 2 and 3.

The coat portion is provided with a collar 16 and with buttons and button-holes 17 and 18 down the front, the opening thus formed being an upward continuation of the fly portion 19, as seen in Figure 1, which is provided with button and button-holes 20.

The garment is provided at the rear with pockets 21 which are carried by the drop seat portion 10, as seen best in Figure 3. 85

The portions 15 which are provided with the button-holes 14 are provided each with a side pocket 22, as seen in Figures 1 and 2, the entrance thereto being formed between the portion 15 and the adjacent portion 23 90 of the leg of the garment.

In practice, after the garment has been put on, the suspender straps are placed over the shoulders and the fastenings 9 engaged with the buttons 7 and the sides of the drop seat portion secured by engaging the buttons 13 with the button-holes 14 and the garment is retained in position. When it is desired to drop the drop seat portion, the fastenings 9 are disengaged from the buttons 7, the 100 buttons 13 are disengaged from the button-holes 14, when the drop seat portion falls into the position shown in Figure 2. When in closed position, the drop seat portion overlaps the lower end of the rear of the coat portion and answers the same purpose as the one-piece garment with the closed back. The cast-off drop seat feature of the construction is deemed most essential, particularly as it drops from a portion a considerable distance below the waistband. 110 and their connection with the seat portions causes any pull on the shoulder portions of the garment to be transmitted to and counteracted by the waist-band 2.

The crossing of the suspender portions 8

5 While the structure hereinbefore described is what is deemed at the present time the most preferable way of carrying out the invention, it is evident that the same is subject to changes, variations and modifications in 10 detail, proportion of parts, etc., without departing from the spirit of the invention or sacrificing any of its advantages. It is, therefore, not intended to restrict the claims to the particular construction and arrangement 15 of parts shown and described, but the right is reserved to make such changes, variations and modifications as come properly within the scope of the appended claims.

What is claimed as new is:—
 20 1. A garment of the character described, embodying a trousers portion, a coat portion and a drop seat portion arranged to drop at a point considerably below the waistband and extended above the bottom of the coat portion of the garment and having suspender 25 straps forming continuations of the seat portion and crossed at the back, the adjacent side edges of the drop seat portion and the garment proper being provided with inter-engaging detachable fastening means, the 30 front portion of the garment having an opening continuous with the fly portion and provided with separable fastening means, and a waistband having its ends detachably connected to the fastening means of said 35 drop seat portion the coat portion having means at the front for detachable engagement with means on the suspender straps.

2. A garment embodying a trousers portion with a drop seat portion, means attached to said drop seat portion for supporting it, a coat portion having pockets on the front thereof, closures for said pockets, and buttons on said closures for detachable connection with said supporting means. 40

In testimony whereof I affix my signature. 45

GEORGE WILLIAM WEAVER.
